Patent expires November 19, 1965

10 Claims. (Cl. 101—279)

1

This invention relates to printing machines wherein sheets are fed to an impression cylinder which co-operates with a printing surface and wherein the impression cylinder is movable into and out of position to contact with the printing surface. The invention is particularly, but not exclusively, applicable to printing machines having sheet detector mechanism for ensuring that only a correctly fed sheet is printed.

The present invention consists in a printing machine providing with mechanisms for feeding, registering and delivering a sheet and having an impression cylinder which is movable into and out of position to contact with a printing surface wherein the feeding, registering and delivery mechanisms are mounted on a support which is moved in accordance with movement of the impression cylinder, said mechanisms continuing in operation irrespective of the position of the impression cylinder and support. Means for operating the feeding and registering mechanisms may be carried by the impression cylinder and may comprise cams which operate said mechanisms through intermediate connections carried by the support.

Preferably the support comprises frames slidable in guideways in side members of the machine frame in which the impression cylinder is mounted. The shaft of the impression cylinder may be mounted in eccentric bearings which are rocked to move the impression cylinder into and out of contact with the printing surface, and the slidable frames may be connected to the bearings so as to move in accordance with movement of the impression cylinder. Each slidable frame may be connected to a bearing by means of a link which is arranged with its lower end embracing a boss on the bearing concentric with the shaft.

The sheet feeding mechanism may include a feed-board which is reciprocated along an extension mounted on the support so as to carry a sheet to the impression cylinder. The sheet registering mechanism may include movable front guides against which the front edge of the sheet is brought, a side registering device which is brought down to the edge of the sheet to register a sheet at the side, and movable drop guides which hold the sheet stationary during the lifting of the front guides and the closing of the impression cylinder grippers on to the sheet. The delivery mechanism may include a delivery chain on sprockets mounted on a shaft which is carried by bearings in the support.

The eccentric bearings in which the shaft of

2

the impression cylinder is mounted may be connected to eccentrics on a shaft which is intermittently given a half rotation by means of a continuously oscillating lever carrying a pawl adapted to be engaged with a notched disc in driving connection with the shaft carrying the eccentrics. Engagement of the pawl with the notched disc may normally be prevented by a trip cam covering a notch in the disc, said trip cam being movable to a position in which the notch is uncovered and the pawl is allowed to engage therewith. Movement of the trip cam may be controlled by manually-operated mechanism or by sheet detector mechanism on the impression cylinder.

The invention will now be described in greater detail with reference to the accompanying drawings, which illustrate one form which it may assume.

20 In the said drawings:

Figure 16 is a side view of the sheet detector

55

mechanism in the impression cylinder, and Figure 17 is a side view of the vacuum box and mechanism forming part of the sheet detector mechanism.

Referring first to Figure 1A, the printing surface comprises a type forme 1 carried by a printing bed 2 which is reciprocated along tracks 3 in a machine frame 4. The upper part of the machine frame 4 has side members 5 carrying bearings 6 for the shaft 7 of a continuously rotating impression cylinder 8, to which cylinder sheets are fed for printing. The bearings 6 are eccentric bearings which may be partially rotated to move the impression cylinder 8 away from the type forme 1 and may be partially rotated in reverse direction to restore the impression cylinder 8 to its original position.

The upper part of each side member 5 is provided with vertical guideways 9 (see Figures 2 and 3) in which a frame 10, hereinafter referred to as a feed frame 10, is slidably arranged. A link 11 connected to each feed frame 10 is arranged with the lower end 12 thereof embracing a boss 13 on the impression cylinder bearing 6 concentric with the shaft 7 and cylinder 8 so that the rotation of the bearings 6 and the rise and fall of the impression cylinder 8 causes the feed frames 10 to move up and down in a vertical plane.

A bracket 14 (see Figure 1A) secured to each feed frame 10 is provided with grooved rollers 15 forming a track along which a feed-board 16 having runners 17 is reciprocated to carry a sheet to the impression cylinder grippers 18. The feed-board 16 is reciprocated by a lever 19, one end of which is forked and engages a stud 19a on the feed-board and the other end of which is provided with a cam roller co-operating with a cam 20 on the impression cylinder 8. Sheets may be fed to the feed-board 16 by any suitable mechanism, such as a swinging suction gripper 21.

Means for operating the impression cylinder grippers 18 may be provided on the side members 5 and feed frames 10. Each feed frame 10 is provided with bearings 22a, 23a and 24a (see Figure 2) for carrying respectively a front guide shaft 22 (see Figure 1A), a side register shaft 23 and a shaft 24 for carrying the sprocket 25 of a delivery chain 26. A support 21a is also provided on each feed frame 10 for a shaft 27 carrying under-guides 28 with which the arms or guides 29 on the front guide shaft 22 co-operate. Studs 30 are provided on the feed frames 10 for the pivotal attachment of drop guides in the form of a transverse bar 31.

The front guide shaft 22 supports means for registering a sheet at the front comprising arms 29a (see Figures 4 and 5) carrying front lays 29. The arms 29a are secured to the shaft 22, to which shaft is attached an arm 32 yielding connected to a cam lever 33 loosely mounted on the shaft 22 and having a cam roller 34 co-operating with cam surfaces 35 (see Figures 2 and 13) formed on the gear 36 attached to the impression cylinder 8. The under-guides 28 on to which the lays 29 are brought down comprise blades attached to arms 37 clamped to the square shaft 27 mounted in the feed frames 10.

The transverse bar 31 (see Figures 6 and 7) forming the drop guides is actuated by a cam 38 secured to the boss 39 of the impression cylinder 8 and intermediate connections 40 (see Figures 11 and 12) mounted on a feed frame 10 comprising a lever 41 having a roller 41a cooperating with said cam 38 and actuating a spring-con-

trolled pusher rod 42 having a lifting member 43 contacting with an adjusting screw 44 on an arm 45 of the transverse bar 31. The adjusting screw 44 effects a quick rise of the transverse bar 31 and permits some adjustment of the timing of the action thereof.

The side register device 23 (see Figures 8, 8a, 9 and 10) comprises a sleeve 46 on which the registering member 47 is adjustably mounted, said sleeve 46 being slidably and rotatably mounted in one feed frame 10, a second sleeve 48 rotatably mounted in the other feed frame 10 but being prevented from endwise movement by a bush 49 and a rod 50 passing through both sleeves 46 and 48. The side-register member 47 is formed with a keypiece 51 which enters and slides in a slot 52 formed in the feed-board edge when the side-register member 47 is rocked in a downward direction. The side-register member 47 is adjustably carried by an arm 53 loosely mounted on the sleeve 46, the arm 53 being connected by means of a spring plunger 54 to a lever 53a adjustably clamped to the sleeve 46. Withdrawal of the spring plunger 54 allows the arm 53 carrying the registering member 47 to be turned to an inoperative position.

The rod 50 has at one end a sleeve 55 with knurled knob 56, the sleeve 55 screwing into a block 57 provided with a recessed washer 58 bearing against a flanged collar 59 secured to the sleeve 46 so that endwise movement of the rod 50 is imparted to the sleeve 46, but the sleeve can be rotated relatively to the block 57 and rod 50. A projecting pin 60 on the block 57 engages a socket in a feed frame 10 to prevent rotation of the block 57 relatively to the feed frame 10 while permitting an endwise movement of the block 57 with the sleeve 46. A spring 61 extending between a collar 62 affixed to the sleeve 46 and one side of the feed frame 10 and a spring 63 extending between the other side of the feed frame 10 and the washer 58 on the block 57 ensure smoothness in the endwise movement of the sleeve 46 in either direction. Rotation of the knurled knob 56 in either direction effects adjustment of the side register member 47 within limits imposed by a stop 64.

The sleeve 46 has secured thereon an arm 65 having an aperture 66 which is slidably engaged by a pin 67 on an arm 68 secured to the second sleeve 48 so that both sleeves 46 and 48 may be rotated together while permitting a sliding movement of the sleeve 46 relatively to the second sleeve 48.

An endwise or sliding movement is imparted to the rod 50 and sleeve 46 by a cam 69 secured to the impression cylinder gear 36 and intermediate connections 70 (see Figures 11 to 14) carried by a bracket 70a secured to the side of a feed frame 10. For this purpose, the rod 50 is formed at its end opposite to that connected to the sleeve 46 with a gib 71 which engages in an aperture 71a formed in a lever 72 secured to a vertical shaft 73 mounted in the bracket 70a, at the lower end of which shaft 73 is secured a toothed segment 74 meshing with a segment lever 75 pivoted by a stud 76 on the bracket 70a. An arm of the segment lever 75 is provided with a roller 77 engaging the cam 69.

The cam 69 is detachably secured to the impression cylinder gear 36 so that it may be removed, reversed and replaced with the outside vertical edge as viewed in Figure 13 placed against the gear 36 so that the endwise or side-laying stroke of the rod 50 can be made to either

side of the normal position, that is to say, so that a sheet may be pushed to either side.

A rotary or oscillating movement is imparted to the second sleeve 48 by a cam 78 secured to the boss of the impression cylinder gear 36 and intermediate connections 79 carried by the bracket 70a. For this purpose the second sleeve 48 has secured thereto an arm 80 pivotally connected at one end to a link 81 which at its other end is pivotally connected to a lever 82 on a horizontal spindle 83 mounted in bearings in the bracket 70a, the other end of the spindle 83 having secured thereto a cam lever 84 having a roller 85 engaging the cam 78.

The means for oscillating the impression cylinder bearings 6, and hence for moving the impression cylinder 8 into and out of contact with the printing surface 1, comprise adjustable links 86 (see Figures 1A and 1B) connected between arms 87 on the impression cylinder bearings 6 and eccentrics 88 secured to a shaft 89 (see Figure 15) mounted in the machine frame. The shaft 89 has also secured thereto a toothed pinion 90 in permanent mesh with a gear wheel 91 rotating freely on a stud 92 secured in the machine frame, the gear wheel 91 having twice as many teeth as the pinion 90. A disc 93 with four evenly spaced notches 94 in its periphery is keyed to the boss 95 of the gear wheel 91 and between the gear wheel 91 and the disc 93, a trip cam 96 is loosely mounted on the boss 95, the trip cam 96 being drawn towards a stop 97 by means of a tension spring 98.

Freely mounted upon the stud 92 is a lever 99 carrying a stud 100 upon which is pivoted a pawl 101 adapted to engage under the influence of a spring 101a with the notches 94 in the disc 93. The lever 99 is connected by a link 102 to a cam lever 103 (see Figure 1B) which is rocked to and fro by a cam 104 on the main cam shaft, once for each revolution of the impression cylinder 8. The parts are so arranged that the pawl-carrying lever 99 moves through ninety degrees for each stroke of the cam lever 103 so that, when the pawl 101 is allowed to engage in one of the notches 94 the disc 93 and the gear wheel 91 are turned through a quarter revolution and consequently the shaft 89 on which the pinion 90 and eccentrics 88 are mounted is caused to perform half a revolution to turn the eccentric bearings 6 and move the impression cylinder 8 towards or away from the printing surface 1. The shaft 89 may be provided with a locking plate 105 (see Figure 15) having notches 106 which are engaged by a roller 107 on an arm 108 influenced by an adjustable spring 109 so that the shaft 89 is held in the position to which it is turned.

The trip cam 96 is normally held away from its stop 97 by a lock arm 110 and covers a notch 94 to prevent engagement of the pawl 101 therewith (as shown in Figure 1B). So long as this condition of the parts is maintained, the pawl 101 rides idly on the periphery of the disc 93 during the to-and-fro movement of the lever 99 and no rotation of the disc 93 and gear wheel 91 occurs.

The lock arm 110 which is pivoted on a stud 111 secured to the machine frame may be given a slight rotation in a clockwise direction by means of a cam 112 which is pivoted to the machine frame and acts on a roller 113 carried by the lock arm 110. Such rotation of the lock arm 110 releases the trip cam 96 and allows it to be moved by the spring 98 into contact with its stop 97, as shown in Figure 15.

Movement of the trip cam 96 uncovers a notch 94, so allowing the pawl 101, when the lever 99 is at the commencement of its stroke, to enter the notch 94. The ensuing movement of lever 99 through ninety degrees rotates the disc 93 through a quarter revolution to cause the shaft 89 to make half a revolution and the impression cylinder 8 to move away from the printing surface 1.

Near the end of its stroke the lever 99 carrying the pawl 101 engages an abutment 114 on the trip cam 96 and so returns the trip cam to the position in which the lock arm 110 again locks it. On the subsequent return movement of the lever 99, the pawl 101 is lifted out of engagement with the notch 94 by the trip cam 96 and remains in disengaged position. When the lock arm 110 is again actuated by the cam 112 the trip cam 96 is again released and the pawl 101 is allowed to engage the next notch 94 to turn the disc 93 and gear wheel 91 through a quarter revolution. The shaft 89 carrying the eccentrics 88 is then turned through half a revolution and the impression cylinder 8 is returned to printing position. The shaft 89 is turned always in one direction, half a revolution effecting the tripping of the impression cylinder 8 and the succeeding half revolution effecting the return to printing position.

The cam 112 is connected by a lever 115 and link 116 to a hand lever 117 (see Figure 16) secured to a shaft 118 journalled in the machine frame. As there are four notches 94 in the disc 93 which could (if allowed by the trip cam) make a quarter rotation for each operative stroke of the lever 99 and each revolution of the impression cylinder 8, it would be possible, by manipulating the hand lever 117, say twice within a single revolution of the impression cylinder 8, to alter the phase relation between the shaft 89 and the impression cylinder 8, so that the latter would then be in a position for contacting with the printing surface 1 at a time when it should be out of such position and vice versa. To prevent the occurrence of this condition, the gear wheel 91 is provided with cam pieces 119 which are arranged to engage a nose-piece 120 on an arm 121 carried by the stud 111. An abutment 122 on the arm 121 engages a similar abutment (not shown) on the cam 112. If the shaft 89 is out of phase with the impression cylinder 8, one or other of the cam pieces 119, through the arm 121, moves the cam 112 into the position it should occupy when the impression cylinder 8 is out of position for contacting with the printing surface 1.

The impression cylinder 8 may be tripped by operation of the hand lever 117 or by the operation of the sheet detector mechanism now to be described, with reference to Figures 16 and 17.

The gripper bar 123 of sheet-receiving grippers 124 on the impression cylinder 8 is pierced with small holes 125 which are in alignment with similar holes 126 in the grippers 124 when the latter are closed on to the bar. The holes 125 are connected by pipes 127 with a vacuum box 128 which is hermetically sealed by a flexible diaphragm 129 and which is located in the impression cylinder 8. A passage 130 in the impression cylinder wall intermittently connects with a fixed port 131 and causes the vacuum box 128 to be put into intermittent communication with an external vacuum chamber 132 which may be exhausted by means of a vacuum pump.

The flexible diaphragm 129 is connected to a pivoted stop finger 133 engaging a notch 134 in a collar 135 secured to a shaft 136 journalled in

the impression cylinder 8. The relation between the diaphragm 129 and the stop finger 133 is such that when the pressure in the vacuum box 128 is less than atmospheric pressure (with consequent deflection of the diaphragm), the stop finger 133 acts in opposition to a spring 131 to hold the shaft 136 against rotation. The shaft 136 projects through an end wall of the cylinder 8, and has secured thereto a cam lever 138 carrying a roller 139 which engages a cam 140 freely mounted on the boss of the impression cylinder and constrained to move in a vertical plane without rotation by a fixed stud 141 which engages a vertical slot 142 in the lower end of the cam 140. The roller 139 is positioned so that normally it passes through a cam slot 143 in a lever 144 attached to the hand lever 117.

A sheet properly held between the grippers 124 and gripper bar 123 closes the holes 125 and 126 and prevents access of air to the vacuum box 128 which has been put in communication with the vacuum chamber 132. The pressure in the vacuum box 128 is then below atmospheric pressure and the flexible diaphragm 129 is deflected downwardly, so holding the stop finger 133 in contact with the notched collar 135 and thereby preventing rotation of the shaft 136. The roller 139 on lever 138 then passes freely through the cam-slot 143.

If there is not sheet between the grippers and gripper bar or if the sheet is incorrectly positioned, one at least of the holes 125 is not covered and air is admitted to the vacuum box 128, so equalizing the pressure on both sides of the diaphragm 129, thus decreasing the deflection thereof and tending to release the stop finger 133 from the notched collar 135. The notch 134 is undercut so that release of the stop finger 133 is deferred until the shaft 136 is given a slight turn by the roller 139 engaging the high part of the cam 140.

The stop finger 133 is then disengaged from the collar 135 and the shaft 136 is free to turn under the influence of the spring 131 to an extent determined by the shape of the cam 140. The position of the roller 139 is now such that it engages with the side of the slot 143 (as shown in dotted lines in Figure 16) and moves the lever 144 and hand lever 117 to trip the impression cylinder 8.

The printing machine continues to run with the impression cylinder 8 out of position for contacting with the printing surface 1 until a correctly fed sheet closes the holes 125 and 126 and restores the impression cylinder 8 to its printing position. When there is no sheet in the grippers 124 the impression cylinder 8 may be moved into position for contacting with the printing surface 1 by operation of the hand lever 117 but the impression cylinder will be automatically tripped on the succeeding revolution of the cylinder unless a sheet has been correctly fed in the meantime.

With a sheet which had been correctly fed but which was defective in length, the impression cylinder 8 would normally remain in position for contacting with the printing surface 1 so that part of the impression would be taken on the impression cylinder packing unless the hand lever 117 were depressed before the position reached by the impression cylinder at which tripping could occur (as determined by cam 40). The time lapse which occurs between the feeding of the sheet to the grippers and the latest point for tripping the impression cylinder gives the operator an opportunity to depress the hand lever 117 in time to prevent set-off of the impression

on to the impression cylinder packing. The impression cylinder is then tripped for one revolution and returns automatically to the position for contacting with the printing surface if the succeeding sheet has been correctly fed.

The sheet feeding and registering mechanism is continuously in operation, a sheet deposited on the feedboard 16 being brought thereby to a position in which the front edge of the sheet abuts against the front lays 29 which have been brought down to the under-guides 28. With the sheet in this position the side-registering member 47 is moved down to the feed-board edge and is then moved transversely so that the key-piece 51 of the registering member 47 enters the slot 52 in the feed-board and the member 47 imparts a side-registering movement to the sheet. The drop guide bar 31 then comes down on to the sheet and at the same time or immediately afterwards the arms 29a rise. The drop guide bar 31 rises almost simultaneously with the closing of the impression cylinder grippers 124 on to the sheet. The drop guide bar 31 holds a sheet stationary at the position of the front lays 29 during the small interval of time between the lifting of the lays 29 and the closing of the impression cylinder grippers 124 on to the sheet. The holding of the sheet by the drop guide bar 31 thus avoids the risk of displacement of the sheet which might occur if the arms 29a were too slowly or too quickly lifted. As the drop guide bar 31 makes contact with the surface of the sheet and moves in a direction substantially perpendicular to the plane of the sheet there is no tendency to disturb the sheet and there is no practical limit to the speed at which the bar may be lifted. Also the drop guide bar 31 interposes a barrier between the hands of the operator and the grippers 124 as the grippers close on to the sheet.

After printing, the sheet may be transferred to a transfer cylinder T and transferred therefrom to a transfer surface T¹ formed on the impression cylinder 8 from which transfer surface T¹ it is taken by grippers on the delivery chain 26, all in the manner disclosed in co-pending patent application No. 710,250, filed Nov. 16, 1946, which has matured to Patent No. 2,508,844, issued on May 23, 1950. It will be appreciated, however, that the present invention is not restricted to use with such transfer and delivery mechanism.

Having described my invention, I declare that what I claim and desire to secure by Letters Patent is:

1. A printing machine including in combination an impression cylinder which is movable into and out of position to contact with a printing surface, mechanism for feeding a sheet to the impression cylinder, mechanism for registering a sheet, mechanism for delivering a sheet from the impression cylinder, a support on which said mechanisms are mounted, eccentric bearings in which the shaft of the impression cylinder is mounted, means for turning the bearings to move the impression cylinder into and out of contact with the printing surface, means for connecting the support to the bearings, and means carried by the impression cylinder for operating said mechanisms.

2. A printing machine according to claim 1 wherein the support comprises vertically slideable frames each of which is connected to a link having its lower end embracing a boss on a bearing concentric with the shaft.

3. A printing machine including in combina-

tion an impression cylinder which is movable into and out of position to contact with a printing surface, mechanism for feeding a sheet to the impression cylinder, mechanism for registering a sheet, mechanism for delivering a sheet from the impression cylinder, a support on which said mechanisms are mounted, means for operating said mechanisms, eccentric bearings in which the shaft of the impression cylinder is mounted, means for connecting the support to the eccentric bearings, eccentrics to which the eccentric bearings are connected, a notched disc in driving connection with the eccentrics, a continuously oscillating lever, and a pawl on the lever adapted to engage the notched disc to rotate same and impart a half rotation to the eccentrics to move the impression cylinder into and out of position to contact with a printing surface.

4. A printing machine according to claim 3 wherein the pawl during one operative stroke effects a quarter rotation of the disc which through gearing effects a half rotation of the eccentrics.

5. A printing machine including in combination an impression cylinder which is movable into and out of position to contact with a printing surface, mechanism for feeding a sheet to the impression cylinder, mechanism for registering a sheet, mechanism for delivering a sheet from the impression cylinder, a support on which said mechanisms are mounted, means for operating said mechanisms, eccentric bearings in which the shaft of the impression cylinder is mounted, means for connecting the support to the eccentric bearings, eccentrics to which the eccentric bearings are connected, a notched disc in driving connection with the eccentrics, a continuously oscillating lever, a pawl on the lever adapted to engage the notched disc to rotate same and impart a half rotation to the eccentrics to move the impression cylinder into and out of position to contact with a printing surface, a trip cam which normally covers a notch in the disc to prevent engagement therewith of the pawl, and means for moving the trip cam to a position in which a notch is uncovered and the pawl is allowed to engage therewith.

6. In a printing machine the combination according to claim 5 including perforated grippers on the impression cylinder, a perforated gripper bar with which said grippers co-operate, a vacuum box mounted in the impression cylinder and connected by passageways to the gripper bar, an external vacuum chamber with which the vacuum box intermittently communicates through a port

in the impression cylinder, a flexible diaphragm mounted in the vacuum box and movable in accordance with the varying pressure conditions in the vacuum box caused by the covering or non-covering of the holes in the gripper bar by a sheet, and means for transmitting movement of the flexible diaphragm to the trip cam.

7. A printing machine including in combination an impression cylinder which is movable into and out of position to contact with a printing surface, a feed board for feeding a sheet to the impression cylinder, mechanism for registering a sheet, mechanism for delivering a sheet from the impression cylinder, a support on which said feed board and said mechanisms are mounted, means for moving the support in accordance with movement of the impression cylinder into and out of position to contact with the printing surface, means carried by the impression cylinder to reciprocate the said feed board along the support towards and away from the impression cylinder, and means carried by the impression cylinder for operating said mechanisms for registering and delivering a sheet.

25 8. A printing machine according to claim 5 including a lock arm normally holding the trip cam in a position covering a notch in the disc and a manually-operable cam which effects movement of said lock arm to release said trip cam and uncover the notch in the disc.

9. A printing machine according to claim 5 including a lock arm normally holding the trip cam in a position covering a notch in the disc and sheet detector mechanism mounted on the impression cylinder and connected to said lock arm to effect movement of the lock arm and uncover the notch in the disc.

10. A printing machine according to claim 5 including an air pressure device, means for varying the air pressure of said device in accordance with the presence or absence of sheets on the impression cylinder, mechanism connected to said device and operable according to variations of pressure therein, and means for transmitting movement of said mechanisms to the trip cam.

FRED SPENCE

It is hereby certified that error appears in the printed specification of the above numbered patent requiring correction as follows:

Column 8, line 70, for the claim reference numeral "5" read 1;
and that the said Letters Patent should be read as corrected above, so that the same may conform to the record of the case in the Patent Office.
Signed and sealed this 4th day of March, A. D. 1952.
